WITNESS:

E. B. Swindle
INVENTOR
BY
Victor J. Evans
ATTORNEY

UNITED STATES PATENT OFFICE.

EDNA B. SWINDLE, OF LANARK, MONTANA.

ATTACHMENT FOR CLOTHESLINES.

Application filed January 3, 1922. Serial No. 526,774.

To all whom it may concern:

Be it known that I, EDNA B. SWINDLE, a citizen of the United States, residing at Lanark, in the county of Sheridan and 5 State of Montana, have invented new and useful Improvements in Attachments for Clotheslines, of which the following is a specification.

The object of this invention is to provide 10 means for preventing clothes when hanging upon a line from being marked by the clothes pins by the use of pads placed on the line.

Another object of the invention is to 15 provide a container for holding the pads when not in use, said container being slidably connected with the line.

A further object of the invention is to 20 make the pads capable of being treated with an anti-freezing solution to prevent the clothes from freezing to the line in cold weather.

This invention also consists in certain 25 other features of construction and in the combination and arrangement of the several parts, to be hereinafter fully described, illustrated in the accompanying drawings and specifically pointed out in the appended claims.

30 In describing my invention in detail, reference will be had to the accompanying drawings wherein like characters denote like or corresponding parts throughout the several views, and in which:—

35 Figure 1 is a view showing the parts in assembled position on a clothes line.

Figure 2 is a view with the parts strung out upon the line.

Figure 3 is a view of the tube 6.

40 Figure 4 is a section on line 4—4 of Figure 1.

In these views 1 indicates the pads which are made of tubular or ring shape so that they can be threaded upon the line. These 45 pads are made of any suitable material, such as cotton, and are of sufficient length to prevent the clothes pin from pressing the clothes against the line, thus preventing pin marks from appearing on the clothes.

The pads when not in use are adapted 50 to be placed in a container 2, the ends of which are closed by removable caps 3, said caps being perforated, as at 4, to receive the clothes line 5. A small tube 6 is threaded upon the wire and is adapted to be placed 55 in the container. The pads are adapted to be threaded upon this tube when not being used and the tube placed in the container.

When the temperature is at the freezing point the pads may be saturated with an 60 anti-freezing solution so as to keep the clothes from freezing on the line. This solution may be injected into the container by a 65 syringe or the like. As will be seen the container and tube are slidably mounted on the line and by providing this container for the pads it is not necessary to remove the pads from the line and they will be kept clean by being enclosed in the container. All parts of the device are formed of non- 70 rusting material.

It is thought from the foregoing description that the advantages and novel features of my invention will be readily apparent.

I desire it to be understood that I may 75 make changes in the construction and in the combination and arrangement of the several parts, provided that such changes fall within the scope of the appended claims.

What I claim is:—

1. An attachment for clothes lines comprising a container having perforated ends for receiving the line and pads of tubular shape located in the container and adapted to be threaded upon the line. 80

2. An attachment for clothes lines comprising a container having removable ends, said ends having central perforations through which the line passes, a tube in the container and adapted to be threaded upon the line and pads of tubular shape threaded upon the tube and adapted to be placed on the line under the clothes pins. 85

In testimony whereof I affix my signature.

EDNA B. SWINDLE.
